UNITED STATES PATENT OFFICE

BENJAMIN C. DA SHIELL, OF SEATTLE, WASHINGTON

DESIGN FOR A KEY TAG

Application filed October 1, 1929. Serial No. 32,906. Term of patent 14 years.

To all whom it may concern:

Be it known that I, BENJAMIN C. DA SHIELL, a citizen of the United States, residing at Seattle, in the county of King and State of Washington, have invented a new, original, and ornamental Design for Key Tags, of which the following is a specification, reference being had to the accompanying drawing, forming part thereof.

Fig. 2 is an edge view of the tag.

I claim:

The ornamental design for a key tag, as shown.

B. C. DA SHIELL.
